SHEET METAL SPROCKET CHAIN LINK AND
METHOD OF MAKING THE SAMEAlford T. Krueger, Milwaukee, Wis., assignor to
Chain Belt Company, Milwaukee, Wis., a cor-
poration of Wisconsin

Application August 9, 1944, Serial No. 548,662

7 Claims. (Cl. 74—251)

1

The invention relates to sprocket chains, and has for its principal object the provision of a simple and relatively inexpensive one-piece sheet metal link for such chains, and a method of making the same which may be conveniently performed by successive die stamping operations.

Briefly stated, the link comprises a pair of spaced parallel side bars which are connected by an integral transverse bridge or cross bar element, an integral extension of which is formed to constitute a pintle barrel or sleeve disposed between the side bars below the bridge and preferably having its end portions received in aligned apertures in the side bars.

For purposes of disclosure one typical example of such a link has been shown in the accompanying drawing forming a part of this specification, with several figures of the said drawing also illustrating the various stages in the processing of a sheet metal blank to produce such link; it being understood however, that those skilled in the art may readily vary the precise details of construction of the link, as well as the precise sequence of steps constituting the process of making it, without departing from the spirit of the invention as defined in the appended claims.

In the said drawing:

Figure 1 is a plan view of a sheet metal blank from which the typical one-piece link is to be formed;

Fig. 2 is a similar view illustrating the next step in the processing of the blank;

Fig. 3 is an edge elevational view, partly in section, of the blank at the stage shown in Fig. 2, and indicating in broken lines the next step in the process;

Fig. 4 is an elevational view as seen from the left of Fig. 3 after the pintle barrel or sleeve has been formed, and showing in broken lines the final step in the formation of the link;

Fig. 5 is a plan view of a pair of the completed links in the relations they occupy when assembled into a strand of chain; and

Fig. 6 is a side elevational view of the links shown in Fig. 5.

Referring more particularly to the said drawing, a blank 10, of generally rectangular conformation as shown in Fig. 1, is stamped from a sheet or strip of metal of suitable thickness. The corners of the blank are preferably rounded substantially as shown in said figure, and either as a part of said initial stamping operation or subsequent thereto, holes 11, 12, 13 and 14 are punched through the blank adjacent the respective corners. The holes 13 and 14, which receive

2

the connecting pintle when the links are assembled into a strand of chain, may be truly circular as shown, while the holes 11 and 12 are of irregular conformation, having segmental lugs 15 and 16, here shown as of approximately 90° in angular extent, and of a radius substantially the same as that of the holes 13 and 14. The radius of the major portion of the holes 11 and 12, which in the instance shown is of substantially 270° in extent, is approximately that of the segmental lugs 15 and 16, plus the thickness of the metal from which the blank is formed. The blank may also be provided with a pair of small perforations 17 intermediate the holes 11 and 12, to relieve distortion at the corners of parts which are subsequently bent as will presently appear.

As a part of the initial stamping operation, or as an operation subsequent thereto, a portion of a central zone of the blank lying between the holes 11 and 13 on one side and the holes 12 and 14 on the other, is struck out to form a tongue 20 having a body portion 21 and a narrower neck 22, with inclined shoulders 23 at their juncture. The neck 22 extends into the perforations 11, between which it remains integrally connected to that portion 27 of said blank zone which is not severed from the blank in the tongue-forming operation. However, the tongue is bent at this point, along approximately the plane indicated by the broken line 24 in Fig. 1, to a position substantially at right angles to the remainder of the blank, as shown in Figs. 2 and 3. At this stage the blank, when viewed in plan as in Fig. 2, presents a pair of spaced legs 25 and 26 which ultimately become the side bars of the link, which legs are connected at one end by the said unsevered portion 27 of the central blank zone, which subsequently becomes the bridge or cross bar element of the link, all as will presently appear.

The right hand portions of the legs 25 and 26 (as viewed in Figs. 2 and 3) are offset relative to the left hand portions thereof, as indicated at 28; and a lug 29 is struck out of a peripheral portion of the pintle hole 14 for engagement with a flat upon or recess in the pintle whereby the latter may be restrained against rotation in the holes 13 and 14. By varying the angle of the offsets 28 the pitch of the link may be varied within limits, as will be readily understood.

As indicated in broken lines in Fig. 3, the body portion 21 of the tongue 20 is next curved to form a partly cylindrical pintle barrel or sleeve 30, the omitted portion of which is of substantially the same angular extent as that of the lugs 15

and 16 in the side bar apertures 11 and 12. To complete the link the leg portions 25 and 26 are now bent relative to the integral bridge 27, along substantially the planes indicated by the broken lines 31 and 32 (Fig. 2) whereby, as is indicated by broken lines in Fig. 4, they are brought to spaced parallel positions with the tongue 26 and its pintle barrel 30 between them and the end portions of the latter entered into the holes 11 and 12 which they snugly fit. The lugs 15 and 16 of the said holes are accommodated by the omitted portion of the barrel but engage with the end face of the tongue and with the shoulders 23, as shown in Fig. 6, whereby they tend to prevent deformation of the barrel under action of the sprocket teeth.

As will be readily understood, the various operations above described may be easily and relatively inexpensively performed by various well known punching, bending and/or die stamping machines; and they will result in the production of a one-piece sheet metal sprocket chain link which is well adapted for numerous purposes.

What is claimed is:

1. A one-piece sheet metal sprocket chain link, comprising a pair of spaced side bars having aligned pintle barrel apertures; a cross bar integrally connecting said side bars; and a pintle barrel integrally connected with said cross bar, disposed between the side bars with its end portions received in said side bar apertures.

2. A one-piece sheet metal sprocket chain link, comprising a pair of spaced side bars having aligned pintle barrel apertures; and a cross bar integrally connecting said side bars and having an integral tongue extending at substantially right angles therefrom between the side bars, the free end portion of the tongue being curved to form a pintle barrel the ends of which are disposed in the side bar apertures.

3. A sheet metal sprocket chain link according to claim 2, wherein at least the end portions of the pintle barrel are of less than 360° in angular extent, and the barrel apertures of the side bars are provided with lugs complementary to and receivable in the omitted portions of the barrel.

4. A one-piece sheet metal sprocket chain link, comprising spaced side bars having aligned pintle barrel apertures, a portion of the tops of said side bars being connected by an integral cross bar element having a depending tongue comprising a neck portion integrally connected to the cross bar and a wider body portion which is curved to constitute a pintle barrel, the ends of said barrel being positioned in the said apertures of the side bars.

5. The method of making a one-piece sprocket chain link from a generally rectangular blank of sheet metal, which comprises displacing a portion of an intermediate zone of the blank to form

an angularly disposed tongue one end of which is integrally connected to the blank; curving said tongue to form a pintle barrel; and angularly displacing the portions of the blank at each side of said intermediate zone in planes at right angles to the plane of displacement of said tongue, to form side bars integrally connected to the undisplaced portion of said blank zone.

6. The method of making a one-piece sprocket chain link from a generally rectangular blank of sheet metal, which comprises displacing a portion of an intermediate zone of the blank to form a tongue extending at substantially right angles to the undisplaced portion of the zone and integrally connected therewith; curving the free end portion of said tongue to form a pintle barrel; and, while maintaining the portions of the blank at each side of said intermediate zone integrally connected to the undisplaced portion of the latter, angularly displacing said side portions relative to said undisplaced zone portion in planes at right angles to the plane of displacement of said tongue, whereby to form side bars positioned at and engaging the ends of said pintle barrel.

10 15 20 25 30 35 40 45 50 55 60 65 70 75 80 85 90 95 100

7. The method of making a one-piece sprocket chain link from a generally rectangular blank of sheet metal, which comprises providing apertures in opposite side portions of the blank; displacing a portion of a zone of the blank intermediate said side portions to form a tongue which extends at substantially right angles to and remains integrally connected with the undisplaced portion of the zone; curving the free end portion of said tongue to form a pintle barrel; and, while maintaining said side portions integrally connected to the undisplaced portion of the intermediate zone, angularly displacing said side portions relative thereto in planes at substantially right angles to the plane of displacement of the tongue, to position the side portions in substantially parallel relation at the respective ends of the pintle barrel and enter such ends into the apertures of the side portions.
